UNITED STATES PATENT OFFICE.

JOHN J. CANNAN, OF ROCHESTER, NEW YORK, ASSIGNOR TO HENRY LIKLY & COMPANY, OF ROCHESTER, NEW YORK, A CORPORATION OF NEW YORK.

GARMENT-SUPPORTING RACK FOR TRUNKS.

1,219,624.

Specification of Letters Patent. Patented Mar. 20, 1917.

Application filed October 31, 1913. Serial No. 798,575.

To all whom it may concern:

Be it known that I, JOHN J. CANNAN, a citizen of the United States, residing at Rochester, in the county of Monroe and 5 State of New York, have invented certain new and useful Improvements in Garment-Supporting Racks for Trunks; and I do hereby declare the following to be a full, clear, and exact description of the same, reference 10 being had to the accompanying drawings, forming a part of this specification, and to the reference-numerals marked thereon.

My invention relates to trunks, and more particularly to the type known generally as 15 wardrobe trunks, in which provision is made for arranging the garments on forms or hangers in extended position, so as to prevent unnecessary creasing or folding, and to the particular class in which the garments 20 are supported on a carrier that is movable relatively to the body of the trunk, the clothing being thus readily accessible when the trunk is used as a wardrobe. A further object of my invention resides in providing a 25 construction that possesses lightness, and is of simple construction, and while capable of being compactly housed when the trunk is closed, can be withdrawn from the trunk in such a manner that the garments will be 30 quite accessible regardless of the size of the trunk. To these and other ends the invention consists in certain improvements and combinations of parts all as will be herein-after more fully described, the novel features 35 being pointed out in the claim at the end of the specification.

In the drawings:

Figure 1 is a view in elevation, showing the trunk in open position, standing on end, 40 with parts broken away, and including a preferred embodiment of the invention;

Fig. 2 is a perspective view of one of the extensible sliding members and the guide on which it is movable, showing the parts dis- 45 assembled for clearness;

Fig. 3 is a sectional view on the line 3^a—3^a of Fig. 5 of the guide;

Fig. 4 is a similar view on the line 4^a—4^a of Fig. 7 taken in a different plane;

Fig. 5 is a vertical sectional view of the trunk with parts broken away, showing the extensible support in its innermost position;

Fig. 6 is a similar view with the support in its outermost position;

Fig. 7 is a sectional view similar to Figs.

5 and 6, showing the extensible support also in section, and

Fig. 8 is a horizontal sectional view through the trunk body, with the extensible support in a position corresponding to 60 Fig. 5.

Similar reference numerals in the several figures indicate the same parts.

In the present embodiment of the invention, which illustrates a preferred arrangement, 1 and 2 designate respectively the hinged sections of a trunk, the section 1 being adapted for supporting the usual garment carrier, which is slidably arranged to permit the garment hangers on the carrier 70 to be withdrawn when the trunk is open, as usual in this class of devices. The garment carrying means is indicated generally at 3, while 4 designates one of the garment hangers supported on the carrying means. 75 The carrier 3 embodies front and rear bars connected by the rods 5, which are arranged intermediate the sides of the carrier, the front and rear bars being mounted on an extensible support consisting of telescoping 80 sections including slides 6, slotted at 7 and provided with lugs 8, all for a purpose that will appear more clearly hereinafter.

The extensible support also includes the U-shaped tracks 9 disposed within the slides 85 6 and provided with pins 10 which engage the aforesaid slots 7 to limit the relative movement of the parts, as shown in Fig. 3. The tracks 9 are movable on stationary guides which are designated generally at 11 90 and are suitably secured to the walls of the trunk, flanges 16 being provided for attachment to the end wall, as shown. Said guides also have U-shaped portions 12 engaging the tracks 9, the movement of the latter being 95 determined by pins or projections 13 on the guides which coöperate with the slots 14 of the tracks. The guides 11 are further provided with lugs 15, which may be integral therewith and are arranged to engage lugs 100 8 on the slides 6, so as to limit the outward movement of the garment carrier, as shown more clearly in Fig. 6.

The construction affords a simple and readily manufactured mechanism, which can be easily applied to a trunk, and enables the garments to be packed in a very compact manner, while at the same time permitting the garment carrier to be withdrawn from its section to a point where the clothes are 110

readily accessible and can be removed or arranged without difficulty.

I claim as my invention:

The combination with the opposite walls 5 of a trunk, of stationary guides secured to said walls having horizontally disposed flanges extending inwardly from said walls, a stop projection extending from one of said flanges, U-shaped tracks, the opposite 10 legs of which engage the flanges of the guide, one of the legs of the track member having an elongated aperture formed therein to receive said stop projection, horizontally dis-

posed stops carried by said track members, and a rectangular frame, the sides of which ¹⁵ are provided with connected flanges, horizontally disposed in engagement with the legs of the U-shaped track member, the connections between said last mentioned flanges having elongated apertures formed therein ²⁰ to receive the stops on said track members.

JOHN J. CANNAN.
